UNITED STATES PATENT OFFICE.

LEIDY J. GARNET, OF LANSDALE, PENNSYLVANIA.

MOLD.

No. 902,722.

Specification of Letters Patent.

Patented Nov. 3, 1908.

Application filed August 24, 1907. Serial No. 389,957.

To all whom it may concern:

Be it known that I, LEIDY J. GARNET, a citizen of the United States, residing at Lansdale, in the county of Montgomery and State of Pennsylvania, have invented certain new and useful Improvements in Molds, of which the following is a specification.

This invention is designed chiefly to provide a metal mold for metal castings, the purpose being to obviate the cost and loss of time attendant upon the use of sand molds in casting metal.

A further purpose of the invention is to devise a mold which will enable the output to be materially increased and to insure working of the casting, which is not possible by the ordinary sand mold.

The invention consists of a sectional mold of metal, having the gate-way at the lowest point and a vent and riser at the highest point and provided with a sprue which is contracted near the receiving end and provided at or near the contracted portion with a vent for the escape of gases.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a transverse section of a mold embodying the invention, the same being taken on the line $x-x$ of Fig. 2. Fig. 2 is a central longitudinal section of a mold on the line $y-y$ of Fig. 1, the dotted lines near each end showing other gates. Fig. 3 is a top plan view of the mold, the dotted lines near each end showing other sprues.

Corresponding and like parts are referred to in the following description and indicated in all the views of the drawings by the same reference characters.

The mold illustrated is designed for casting pipe or hollow columns or pillars and comprises a pair of molds having a sprue and gate common to both and arranged between them. Each mold consists of four sections 1, 2, 3 and 4, which are snugly fitted together and adapted to be clamped or secured in any

substantial way. The several mold sections are formed of metal, gray iron being preferred, although any metal may be employed best adapted to the nature of the articles to be cast. The mold is provided at the highest point with a riser and vent 5, the same consisting of an opening formed between vertical flanges 6 and 7 provided at the upper edges of the sections 1 and 2. The combined riser and vent or opening 5 increases in width from bottom to top, with the result that the surplus metal may be easily removed.

The core 8 may be of any construction commonly resorted to in the formation of pipes, columns or the like, and is confined within the sections so as to leave a space corresponding to the shape of the article to be cast. The entrance opening 9 is located at the lowest point of the mold and constitutes the gate through which the molten metal finds its way into the mold during the casting operation. The sprue 10 is arranged between the two molds and is common thereto and gradually widens from a point near its upper end towards the bottom where it leads into the chamber 11 which is in communication with the openings or gates 9. The sprue 10 flares at its receiving end, as indicated at 12, and is contracted at 13, a short distance from the upper end and from the point 13 to the chamber 11 the sprue gradually flares. A vent 14 leads outward from the sprue at or near the contracted end 13 and provides an escape for hot air and gases.

A base 15 is provided to support the two molds, and the chamber 11 is formed in the upper portion thereof intermediate of its longitudinal edges. A core 16 is arranged in the bottom of the chamber 11 directly in line with the sprue 10 and is formed of sand and receives the molten metal as it descends through the sprue 10 and deflects the same without producing chill. The bottom of the chamber 11 at each side of the core 16, is supplied with a protector 17, the same consisting of a steel plate which receives and allows the molten metal to flow thereover without knitting. Opposite ends of the chamber 11 are made rounding and lead into the opening or gates 9, thereby preventing formation of corners or angular spaces in which the metal would tend to lodge and accumulate.

By having the sprue widening from the points 13 towards the chamber 11, the molten metal has a free drop from the point 13 to the

chamber without touching sides of the sprue and becoming chilled. By having the gate or opening 9 at the lowest point of the mold, the hot air and gases pass upward through the mold in advance of the molten metal, thereby heating the walls of the mold in advance of the molten metal and preparing the mold so as to insure the formation of a perfect casting. By having the vent and riser 10 at the extreme top of the mold, all hot air and gases may readily escape and all dross and imperfect metal may pass off through the vent and thereby increase the chances for a perfect casting.

15 The number of sprues and gates vary according to the length of casting to be formed and the amount of metal required for the casting. The vent 5 extends the entire length of the mold space to provide an escape for the air so that a perfect casting may be obtained at each pouring.

Having thus described the invention, what is claimed as new is:

1. In combination, a mold, an approximately vertical sprue gradually increased in width from a point at or near the top towards the bottom, a chamber at the lower end of the sprue and in communication with the mold, a core of sand or like material let

into the bottom of said chamber and arranged 30 in vertical line with said sprue, and a plate of steel forming the bottom of said chamber at one side of the said core.

2. In combination, companion molds, a sprue arranged between the molds and common to each and gradually increasing in width from a point at or near its top to its bottom, a chamber in communication with the said molds and having the sprue opening therein at a central point, a core of sand or 35 like material arranged upon the bottom of the chamber in vertical line with the sprue, and protective plates of steel covering the bottom of the chamber at each side of the said core.

40 3. In combination, with a mold, a sprue having communication therewith and flared at its upper end and gradually widening from the lower end of the flared portion towards its lower end and having a vent at or 45 near the contracted portion provided near its upper end.

In testimony whereof I affix my signature in presence of two witnesses.

LEIDY J. GARNET. [L. S.]
